[57] CLAIM

The ornamental design for a shoe upper, as shown and described.

DESCRIPTION

FIG. 1 is a side elevational view of one side of a shoe
upper showing my new design;

FIG. 2 is a side elevational view of the other side of the shoe upper shown in FIG. 1;

FIG. 3 is a front elevational view of the shoe upper
shown in FIG. 1;

FIG. 4 is a rear elevational view of the shoe upper shown in FIG. 1; and

FIG. 5 is a top plan view of the shoe upper shown in FIG. 1.

The broken line showing of a shoe sole, including the upper vertical sides of the sole, is for illustrative purposes and forms no part of the claimed design.
